UNITED STATES PATENT OFFICE.

MICHEL MONCION, OF OGDENSBURG, NEW YORK.

FREEZER OR REFRIGERATOR.

SPECIFICATION forming part of Letters Patent No. 416,417, dated December 3, 1889.

Application filed July 26, 1889. Serial No. 318,771. (No model.)

To all whom it may concern:

Be it known that I, MICHEL MONCION, a subject of the Queen of Great Britain, residing at Ogdensburg, in the county of St. Lawrence 5 and State of New York, have invented a new and useful Improvement in Freezers or Refrigerators, of which the following is a specification.

This invention relates to improvements in 10 freezers or refrigerators for making ice and preserving articles of food; and it consists in the construction, combination, and arrangement of parts, as will be hereinafter described and claimed.

15 In the accompanying drawings, Figure 1 is a perspective view. Fig. 2 is a vertical cross-section on the line $x-x$, Fig. 1. Fig. 3 is a horizontal section on the line $y-y$, Fig. 1.

Similar letters of reference indicate corresponding parts.

20 A represents the outer case of the freezer, which may be of any desired shape or size and is constructed of wood or other suitable material. This case is provided with an inner wall or lining B of wood, so arranged as to leave a space a between the walls, which is filled with sawdust or other non-conducting material.

25 C represents a freezing or cooling chamber, the walls of which are constructed of metal. At the sides and back of the cooling-chamber is arranged a refrigerant-chamber D, in which is placed a mixture of ice and salt. The inner walls of the ice-chamber are formed by 30 the outer sides of the cooling-chamber and the outer walls by a metal partition b, which extends from the bottom of the refrigerator nearly to the top or cover I. The ice-chamber may be made in three parts, if desired, 35 forming separate chambers arranged, respectively, at the sides and back of the cooling-chamber.

40 Between the outer wall b of the ice-chamber and the lining B of the case is formed a space or chamber E, which is filled with common dry salt. The salt is used to absorb moisture, and also by its non-conducting properties to assist in preserving the ice in the chamber D. I have found that salt is the 45 best material for this purpose, although, if desired, other non-conducting substances may be used.

The bottom G of the freezer may be made with double walls, like the sides, the intervening space being filled with non-conducting 55 material.

Small tubes or openings c, leading from the ice-chamber, extend through the bottom of the freezer for the escape of water formed from the melting ice.

60 The external case A is provided with a hinged lid or top cover H and an under cover I. In the under cover I are formed apertures or feeding-holes d, through which the salt and the mixture of ice and salt are placed in the 65 chambers E and D.

J represents covers or lids for closing the feeding-holes in the top I. The top cover or lid H has downwardly-projecting flanges, which, when the lid is closed, assist in excluding the air more effectually from the 70 freezer.

K is the door of the cooling-chamber C. This door, as well as the lids J and the cover H, may be provided with packing, so as to form 75 air-tight closures.

75 After the mixture of ice and salt is placed in the chamber D, a quantity of laundry-bluing dissolved in water is poured over it, forming a cement or crust e, which by excluding 80 the air assists in preserving the ice. Other materials may be used for coating the ice; but I have found by repeated experiments that bluing is the best material for this purpose. By this construction and arrangement 85 a very low temperature is produced, and water placed in pans and introduced into the chamber C is readily converted into ice. A portion of the ice thus formed can be used for keeping the freezer in operation. The apparatus can also be used as a refrigerator, and articles of food, as meat, fish, milk, &c., can be 90 economically preserved.

Having thus described my invention, what I claim as new, and desire to secure by Letters 95 Patent, is—

1. In a freezer or refrigerator, the combination, with a double-walled outer case filled with non-conducting material, of the salt tank or chamber arranged within the case, a refrigerant or ice chamber inside of the salt-tank, and a central cooling-chamber, arranged substantially as set forth.

2. In a freezer or refrigerator, a cooling-

chamber having a door in front, a refrigerant or ice chamber at the sides and back of the cooling-chamber, a salt-tank arranged outside of said refrigerant-chamber, and an external 5 case provided with feed-holes for filling the refrigerant and salt tanks, substantially as shown and described.

3. In a freezer or refrigerator, a chamber for the reception of articles to be cooled or 10 frozen, a tank or chamber arranged outside

of the cooling-chamber, a refrigerant contained in said tank, a cement or coating forming an air-tight covering for said refrigerant, a cover provided with holes for filling said refrigerant-tank, and lids for closing said 15 holes, substantially as herein set forth.

MICHEL MONCION.
